UNITED STATES PATENT OFFICE.

BENJAMIN F. MCGUINNESS, OF GRAFTON, MASSACHUSETTS, ASSIGNOR TO CROMPTON & KNOWLES LOOM WORKS, OF WORCESTER, MASSACHUSETTS, A CORPORATION OF MASSACHUSETTS.

TUBE FRAME.

Application filed November 6, 1923. Serial No. 673,183.

To all whom it may concern:

Be it known that I, BENJAMIN F. MCGUINNESS, a citizen of the United States, residing at Grafton, in the county of Worcester and State of Massachusetts, have invented a new and useful Tube Frame, of which the following is a specification.

This invention relates to tube frames for Axminster looms and more particularly to the hooks by which the frames are held to the chains ordinarily employed in Axminster looms.

Looms of this type have on each side thereof endless chains made up alternately of double and single links and the tube frames are usually provided with brackets, each having a rigid tongue which passes into the double links. In order to hold the tube frame to the chain there are provided spring hooks, the lower ends of which are screwed to the brackets and the upper end of which is hook-shaped to engage the inner one of the corresponding double links.

The usual construction is such that the tongue is offset from the end of the tube frame and the spring which is secured to the body of the bracket is necessarily inclined with respect to the axis of the tube frame. The result of this is that the strain on the spring hooks incident to supporting the tube frame acts obliquely to the length thereof, thus producing an inward as well as downward pull on the spring hooks. This inward pull tends to disconnect the spring hooks from the chains with the result that the tube frames fall out of position. Also, it is found that the screws by means of which the hooks are held to the brackets work loose, partly because of the strain exerted lengthwise of the tube frame.

It is one object of my invention to overcome these defects by providing means whereby the strain of supporting the tube frame is transmitted from the chain to the bracket or some part thereof in a line substantially perpendicular to the axis of the tube frames. In carrying out the invention I form a hook of rigid non-flexible material and mount the same for sliding motion endwise of the tube frame so that all angular movement of the hook with respect to the tube frame is obviated.

A further object of the invention is to provide means for interlocking the tube

frame and its transfer arms in such a way as to assist the proper operation of the stop motion provided to stop the loom when the tube frames are not released from the chains.

With these and other objects in view, which will appear as the description proceeds, the invention resides in the combination and arrangement of parts hereinafter described and pointed out in the claims.

Referring to the drawings, wherein one form of my invention is shown,

Fig. 1 is a front elevation of a portion of a tube frame constructed according to my invention together with parts of the associated transfer clutch,

Fig. 2 is an end elevation of the tube frame shown in Fig. 1, and

Fig. 3 is a vertical section on line 3—3 of Fig. 2 with the transfer clutch shown in vertical section.

In carrying out my invention, I provide a tube frame 10 to which are fastened the yarn tube sections 11, one of which is indicated on the drawing. The spool 12 is mounted on the spool bearing 13, the lower end of which is bent to extend into the tube frame 10 as indicated at 14. The chain engaging bracket 15 has the lower end formed as at 16 similarly to the lower end of the spool bearing, while the upper end thereof has an offset tongue 17 arranged to pass between the links 18 of the supporting chain.

The transfer clutch 20 is provided with an inclined cam surface 21 and is connected to the transfer arms (not shown) of the loom by means of stud 22. The matter thus far described is in common use and forms no essential part of my invention.

Referring to Fig. 3 it will be seen that I have provided a stud 30 riveted or otherwise secured in the adjacent vertical portions of the spool bearing and chain engaging brackets 13 and 15, respectively. The chain engaging hook 31 is formed at the upper end of the sliding member 32 which is formed with wings 33 arranged to lie in recesses 34 formed on the opposite vertical edges of the bracket. The wings and recesses lie on opposite sides of the stud 30, and the latter passes through the member 32 and has a head 34 to limit outward motion of the hook under influence of spring 35 which surrounds the stud and serves normally to force the hook outwardly. The lower end of the

member 32 is bent as at 36 and extends under the adjacent ends of the tube frame and in sliding contact therewith.

The clutch 20 is formed as an upstanding 5 arm 37 in which is threaded screw 38, the inner end of which is hollow as indicated at 39 in Fig. 3. A lock nut 40 may be employed to lock the screw 38 in position. The opening 39 is designed to be opposite the stud 30 10 when the clutch and tube frame are in operative relation.

The inner upper edges of the chain links 15 18 are bevelled as indicated in Fig. 1 and it is therefore necessary to raise the tube frame slightly before disengaging the hook. When the tube frame is about to be lifted from the chain, the clutch 20 is moved inwardly toward the end of the frame and the lower inner part of the cam face 21 engages the 20 outer lower end of member 32, the result of which is to raise the tube frame and thus carry the bottom of the hook 31 above the adjacent chain link. As the clutch 20 continues to move inwardly the inner end of 25 the screw 38 engages the member 32 on opposite sides of the stud 30 and moves the same inwardly against the spring 35 until the hook is out of vertical alignment with any part of the chain, at which time the parts will assume the position shown in Fig. 3. The clutch is then lowered to move the 30 yarn tubes into weaving position.

The sliding member 32 is made substantial enough to support the tube frame and it 35 will be seen because of this construction that the strain of supporting the tube frame is transmitted to the chain substantially at right angles to the length of the tube frame. The wings 33 serve to guide the hooks so that the spring 35 will be compressed easily 40 and cramping avoided. The guiding of the hook is further effected by the bent end 36 passing under the tube frame, the use of this bent end making it possible first to raise 45 the hook by the cam 21 so that it may subsequently be given a parallel motion away from the chain. Also, it will be observed that when the clutch is in position to be lowered the sliding member 32 will lie in 50 opening 39 and should the tube frame be held up through some faulty action of the releasing hook, the clutch and its transfer arm will be held up to throw into operation 55 the stop motion (not shown) for arresting the loom.

Having thus described my invention, it will be evident that changes and modifications may be made by those skilled in the art without departing from the spirit and scope of the invention as set forth in the appended claims, and I do not wish to be otherwise limited to the details herein disclosed.

What I claim is:

1. In a tube frame for Axminster looms, 60 a longitudinally extending frame member, a

chain engaging element rigid with respect to the member, and a chain engaging hook mounted for sliding movement with respect to the member element, said hook being movable as a whole toward and from the said 70 element, and all portions of said hook having substantially the same amount of motion.

2. In a tube frame for Axminster looms, a bracket carried by the end of the frame, a chain engaging hook, coacting elements on the bracket and hook to define sliding connection between said bracket and hook to give said hook a parallel motion, and means 75 acting in substantial alignment with the coacting elements to move said hook. 80

3. In a tube frame for Axminster looms, a bracket carried by the end of the frame, a chain engaging hook member associated with the bracket and supported thereon, means to move said hook member longitudinally of the frame, and means to guide said hook member to keep said hook member substantially perpendicular to the tube frame in all positions thereof. 85

4. In a tube frame for Axminster looms, a bracket for supporting the tube frame having an extension substantially parallel to the axis of the tube frame, and a hook mounted on said extension and slidable thereon in a direction parallel to the axis 95 of the tube so that all portions of said hook have the same amount of motion with respect to the tube frame. 90

5. In a tube frame for Axminster looms, a bracket secured to the tube frame, and a chain engaging hook having a portion, 100 mounted for sliding engagement with respect to the bracket and having another portion passing under and having sliding contact with the underside of the tube frame. 105

6. In a tube frame for Axminster looms, a supporting bracket secured thereto, a chain engaging hook member, and means defining a sliding connection between said hook member and the bracket and also between said hook member and the tube frame. 110

7. In a tube frame for Axminster looms, a supporting bracket secured thereto, a chain engaging hook member having wings 115 in sliding contact with the bracket to guide the hook member and a supporting stud carried by the bracket and extending through the hook.

8. In a tube frame for Axminster looms, a bracket secured thereto having a stud projecting therefrom substantially parallel to the axis of the tube frame, a hook member guided on the stud, and means to engage the hook member on opposite sides of the stud and move said hook on said stud substantially parallel to the axis of the tube frame. 120

9. In a tube frame for Axminster looms, a supporting bracket secured thereto and having a stud extending therefrom in the direction of the length of the tube frame, a chain 125

- engaging hook member slidably mounted on the stud, and means to engage the hook member and move the same on the stud, said means being recessed to receive the stud 5 when the hook member is moved to chain releasing position.
10. In a tube frame for Axminster looms having a clutch provided with a cam face, a hook member mounted for movement with respect to the tube frame having a portion 10 in the path of the cam face of the clutch to be lifted thereby and connections between the hook member and the tube frame whereby the latter is raised when the said member 15 is lifted.
11. In a tube frame for Axminster looms, a bracket secured thereto, a hook member slidably mounted with respect to the bracket and having a portion extending under the 20 tube frame, and means first to engage said portion of the hook directly to raise the latter and thereafter to move said hook member toward the bracket.
12. A hook member for Axminster tube frames having a chain engaging bracket on each end thereof slotted to receive the hook member and provided with auxiliary guides, said hook member having a chain engaging portion at one extremity, an offset portion 25 at the other extremity to extend under the tube frame, and guiding portions intermediate the extremities to cooperate with the auxiliary guides.
13. A hook member for tube frames for Axminster looms having a bracket on each end thereof slotted to receive the hook member and provided with auxiliary guides, said hook member having a chain engaging portion 30 at one extremity and a portion formed adjacent the other extremity for sliding contact with the tube frame, said hook member being also provided with guides to cooperate with the auxiliary guides.

In testimony whereof I have hereunto affixed my signature.

BENJAMIN F. McGUINNESS.
